[57] **CLAIM**

The ornamental design for a timing device for fishing rods, substantially as shown and described.

DESCRIPTION

FIG. 1 is a perspective view of a timing device for fishing rods showing my new design.

FIG. 2 is a top plan view thereof.

FIG. 3 is a side elevational view thereof as seen from the bottom side of FIG. 2.

FIG. 4 is a side elevational view thereof as seen from the top side of FIG. 2.

FIG. 5 is a front elevational view thereof.

FIG. 6 is a rear elevational view thereof.

FIG. 7 is a bottom plan view thereof.

FIG. 1

FIG. 2

FIG. 3

FIG. 4

FIG. 5

FIG. 6

FIG. 7
